CLAIM

The ornamental design for a bench, as shown and described.

DESCRIPTION

FIG. 1 is a front right perspective view of a first embodiment of a bench according to the new design;
FIG. 2 is a rear left perspective view thereof;
FIG. 3 is a front elevational view thereof;
FIG. 4 is a right side elevational view thereof;
FIG. 5 is a left side elevational view thereof;
FIG. 6 is a rear elevational view thereof;
FIG. 7 is a top view thereof;
FIG. 8 is a bottom view thereof;
FIG. 9 is a front right perspective view of the bench of FIG. 1, shown in a different environment of use;
FIG. 10 is a front right perspective view of the bench of FIG. 1, shown in a different environment of use; and,
FIG. 11 is a front right perspective view of a second embodiment of a bench.
The dash-dotted lines in FIGS. 9 and 10 illustrate environmental subject matter and forms no part of the claimed design. The evenly broken lines in the drawings illustrate portions of the bench and form no part of the claimed design.

1 Claim, 11 Drawing Sheets
